UNITED STATES PATENT OFFICE.

JOHN E. FINNEGAN AND PATRICK J. McCARTHY, OF PROVIDENCE, RHODE ISLAND.

CASKET.

1,310,860.

Specification of Letters Patent. Patented July 22, 1919.

Application filed May 9, 1919. Serial No. 295,971.

To all whom it may concern:

Be it known that we, JOHN E. FINNEGAN and PATRICK J. McCARTHY, citizens of the United States, residing at Providence, 5 in the county of Providence and State of Rhode Island, have invented a new and useful Improvement in Caskets, of which the following is a specification.

This invention relates to certain new and 10 useful improvements in caskets, and the primary object of the invention is to provide a casket which has an exterior shell of thin metal and a wood or similar interior, the wood acting to brace and reinforce the thin 15 metal shell, and being applied thereto subsequent to the formation of the shell.

A further object of the invention is to 20 provide a novel manner of securing the wood filler within the shell, and to also provide a lid or cover formed in a manner generally similar to the formation of the body of the casket.

Further and other objects will later appear and be manifested in the course of the 25 following description.

In the drawings—

Figure 1 is a top plan view of a casket formed according to the present invention.

Fig. 2 is a side elevation.

30 Fig. 3 is a transverse section taken through the body of the casket, and

Fig. 4 is a similar view of the top or lid.

In proceeding in accordance with the present invention, an exterior shell 1 is 35 formed by use of suitable dies or rolls, the shell so formed being an integral or one-piece structure, and having the molding 2, 3, extending along the sides and ends thereof, the molding being hollow and 40 opening into the shell interior. The upper side of the shell is originally formed as indicated in dotted lines at 4, in Fig. 3, whereupon the filler pieces 5 and 6 are first inserted in the molding from the shell interior 45 so as to lie flush with the inner side faces of the sides and ends of the body 1, following which the side and end boards or wood filler pieces 7 are inserted and the bottom filler board or piece 8 also applied. These

boards or pieces 7 will abut and retain the 50 molding filler pieces 5 and 6, in position, the bottom board acting to hold the side filler pieces in their spread or spaced relation. The portion 4 of the thin metal shell is next 55 bent over and downwardly so as to engage on the top faces of the filler pieces 6 of the molding, and on top of the upper edges of the filler pieces 7—7 and in engagement with the inner side faces of the filler pieces 7—7 being preferably inset or countersunk in 60 the latter as shown at 9 in Fig. 3 of the drawings. The edge portion 4 when bent into the finished form depicted in Fig. 3 acts to cover the joint between the filler pieces 6 and 7, and to also hold same firmly together. 65

The top is formed in a similar manner with a thin metal shell 11 configured as desired and a wood filler 10, the edges 12 of the shell being bent into engagement with 70 the wood filler from the dotted to the full line position of Fig. 4.

It will be apparent that the entire thin metal shell is thoroughly braced throughout, and all of the filler pieces are firmly held 75 by engagement with one another and with the shell as Fig. 3 illustrates.

Having thus described our invention, what we claim and desire to secure by Letters Patent is—

1. In a casket, a thin metal shell formed with upper and lower outwardly extending hollow moldings along the sides and ends thereof, the moldings opening into the shell interior, filler pieces in the hollow moldings 85 arranged flush with the inner side faces of the sides and ends of the shell, filler boards engaged with said filler pieces and disposed along the ends and sides of the shell, and a filler board in the bottom of the shell engaged with the filler boards, the upper edges of the shell being inturned and countersunk in the inner faces of the filler boards of the ends and sides. 90

2. In a casket, a metal shell having moldings formed along its top and bottom, filler pieces in the moldings, filler pieces for the ends and sides of the shell engaged with 95

the filler pieces of the moldings, and a bottom filler piece for holding the side and end filler pieces in position, the top of the shell being bent inwardly to overlie the top filler pieces of the moldings and the top edges of the side and end filler pieces.

In testimony whereof we have signed our

names to this specification in the presence of two subscribing witnesses.

JOHN E. FINNEGAN.

PATRICK J. McCARTHY.

Witnesses:

ADA E. HAGERTY,

J. A. MILLER.
